VEHICLE TIRE

Charles G. Wyman, Devon, and William B. Dunlap, Jr.,
Blue Bell, Pa., assignors to Lee Rubber & Tire Corporation,
Conshohocken, Pa., a corporation of New York

Filed Sept. 10, 1962, Ser. No. 71,634

Term of patent 14 years

(Cl. D90—20)

FIG. 1.

We claim:

The ornamental design for a vehicle tire, as shown.
